UNITED STATES PATENT OFFICE

2,461,711

COMPACT

Albert Wewetzer, Elgin, Ill., assignor to Illinois Watch Case Co., Elgin, Ill., a corporation of Illinois

Application March 24, 1945, Serial No. 584,542

4 Claims. (Cl. 220—31)

1

This invention relates in general to a cosmetic container for powder, rouge, and the like, and is more particularly described as a compact made partly or entirely of plastic material.

An important object of the invention is to provide a cosmetic container in which the parts are made and combined in such a manner that the entire structure may be made entirely of plastic materials.

A further object of the invention is to provide an improved cover structure and hinging arrangement therefor by which it may be attached in a container.

A further object of the invention is to provide a new and improved cover fastening and opening means in connection with a cover mounted to fit flush in a cosmetic container.

Still a further object of the invention is to provide a powder compartment at the bottom of a cosmetic container which may be opened and closed by means of a slideable lid.

Other objects of the invention will appear in the specification and will be apparent from the accompanying drawings, in which:

Fig. 1 is a perspective view of a compact in accordance with this invention showing the compartment lid and the cover both partially open;

Fig. 2 is a plan view of the structure shown in Fig. 1 with the hinge and cover removed;

Fig. 3 is a sectional view as taken on line 3—3 of Fig. 2 but with the cover in place and partially open;

Fig. 4 is a sectional view taken on line 4—4 of Fig. 3;

Fig. 5 is a perspective view from the under side of the frame and platform structure;

Fig. 6 is a perspective view of the under side of the cover;

Fig. 7 is a perspective view of a transverse hinge plug for the cover;

Fig. 8 is a detail in section, taken on line 8—8 of Fig. 1;

Fig. 9 is a perspective view of a compact having a modified cover and hinge construction, the compartment lid and the cover being partially open;

Fig. 10 is a sectional view of the compact shown in Fig. 9 with the cover in closed position;

Fig. 11 is a sectional view of the structure shown in Fig. 9 with the cover in open position;

Fig. 12 is a sectional detail of the hinge mounting taken on line 12—12 of Fig. 11;

Fig. 13 is a perspective view of the hinge plug as shown in Figs. 10 and 11;

Fig. 14 is a perspective view of one corner of the

2

base to show the hinge plug and cover hinge mounting structure; and

Fig. 15 is a perspective view of the rear hinging edge of the cover shown in Figs. 9, 10 and 11.

Cosmetic and other similar pocket containers have heretofore been produced in a large variety of forms and constructions, some made of metal alone, and some combining metal and various plastic walls or pieces. The compact of the present invention is designed and intended to provide a container in which all of the material parts may optionally be constructed of plastic materials.

Referring now more particularly to the drawings, the base B is formed of any desired or suitable plastic material having sufficient thickness to form a substantially flat container and having any desired outer decorative contour or appearance. In the top face of the container is a substantially rectangular opening defining a recess 17 having a shoulder 18 around the upper edge to receive the edge of a cover C therein flush with the top or upper face of the base. At the top of the front wall 15 of the base is a notch 20 extending outwardly from the central portion flush with the shoulder 18 and formed upon the front of the cover is a lip 21 to extend outwardly in the notch. This lip may project slightly beyond the outwardly rounded portion of the base so that the finger or finger nail of a person may be inserted below the lip to pry or force the cover upwardly in opening it.

In the bottom of the recess 17 is a compartment 22 for powder or other material, defined in part by a frame having a marginal rim 23 extending around the opening at the front and sides thereof to support a thin cross platform 24 connecting the top of the frame over its rear and sides, leaving an opening adjacent the front rim.

At the front and in the opposite sides of the recess 17 are slots 25 located just above the upper edge of the frame and the platform supported thereby, so that a flexible lid 26, desirably of plastic, may be initially sprung (as indicated in broken outline in Fig. 4) to seat opposite edges thereof in the side slots 25 for sliding engagement over the top of the frame for opening and closing the compartment therewithin. The top of the lid may be provided with a plurality of grooves 27 constituting, in effect, a finger piece whereby to facilitate manual engagement with the lid for operating purposes.

With this compartment construction, the frame may be secured in place within the recess 55 in any of various ways, as by adhesion, by a

tight friction fit, by fusion of the material, or otherwise. I aim to provide a tightly sealed compartment for receiving powder or other material therein, the lid fitting closely but slidably in the slots and overlapping the platform and frame to provide a sufficiently leak-proof connection to prevent escape of powder. In such a construction the lid may nevertheless be moved easily for opening or closing the compartment as desired.

At the rear of the cover C, is a hinge pintle in the form of an enlarged rounded bar 28 connected to the cover by a web 29 which stops short of the bar ends to form at such points open-ended slots 30. The two end portions of the bar are adapted to be seated in a pair of aligned slotted channels 31 having interior contours extending for the major part of a circle, these two channels constituting spaced hinge bearings wherein the bar ends are free to be rotated. The channel bearings are formed upon the upper edge of a plug 32 which is fitted into the recess 17 within a space provided for the purpose between the frame and the rear wall 16 of the base, the ends of the plug being extended into vertical notches 33 that are formed in the base side walls at their juncture points with the rear wall 16 of the base. To assemble the cover hinge parts, the pintle is slid endwise within the channels of the plug prior to fitting of the latter within the base; when assembled, and the plug is secured in its final position, the base side walls then extend over the ends of the bars whereby to prevent any endwise movement between the cover and its hinge plug. When so positioned, the marginal edge of the cover C will seat upon the shoulder 18 in flush relation with the upper side of the base. Opening movement of the cover is arrested by engagement of its web with the rear channel wall 34 that is extended upwardly from the plug and preferably continuously for its length. Extending from the inside of the cover C is a flange 35 spaced from the marginal edges of the cover to fit within the recess and to provide a space for receiving a mirror 36 which is adhesively, or otherwise, secured within the flange.

Projecting from the central portion of the outer flange of the cover is a rib 40 adapted to engage in a locking groove 41 of corresponding length, the resiliency of the parts permitting the rib to flexibly engage in the groove, whereby to seat the cover tightly against the shoulder 18 in its closed position.

With this construction, the compact, with the exception of the mirror, which may be of glass, metal, plastic, or any suitable material, may be made entirely of plastic material, the parts being secured together by heat and pressure, by an adhesive, or by any method as now commonly employed, and, when thus constructed and combined, they will produce a light, strong, effective and efficient compact or container.

In the modification of the hinge structure, as shown in Figs. 9 to 15, a cover C has a hinge projection 45 which curves downwardly and arcuately at the rear with an outwardly slightly projecting rib 46 at its extremity.

The rear wall 41 of the compact base B on which the cover is mounted, is formed with a hinging groove having a portion 49 concavely rounded in cross section with upper and lower edges 50 and 51, respectively, at an angle thereto. A lip 50 is formed at the upper edge of the groove in a slightly overhanging position. At the ends of the lower edge 51 are notches 52 at the sides of the recess wherein are rested lugs 53 projected

beyond the ends 54 of a hinge plug 55 having a laterally extended rounded bead 56 to fit the curved under side of the hinge projection 45 of the cover. When the hinge plug is in place, its 5 end lugs occupy positions within the notches 52 between end shoulders of the adjacent base sides and bosses 57 one formed medially of each notch. The hinge projection 45 then is confined in the space between the plug and the rear wall 41 of the compact base B, being free to move arcuately therewith through more than 90° to permit the cover to swing from a closed position where it is rested upon the base shoulders 18 to a fully open position where the hinge projection edge adjacent the rib 46 engages the plug below its bead (see Fig. 11). The bosses 57 which desirably are curved in conformity with the curved under side of the cover rear projection 45, act in cooperation with the arcuate groove 49 to confine the cover to movements about a fixed axis. When in closed position, the cover arcuate rear edge is extended down sufficiently far below the top edge 50 of the concave groove 49 so as to be prevented thereby from becoming disconnected from the base.

The compartment, sliding lid, and other features of the cover construction, may be substantially as shown in Figs. 1 to 5, and where corresponding thereto, are designated by reference numerals the same as used in connection with those figures.

In constructing a container of this kind, it is important to have the hinge and other joints fit strongly and tightly to prevent powder from escaping therethrough, or clogging the joint. By interlocking and adhesively securing either one of these hinge plugs in place, a satisfactory swinging connection for the cover is provided, and one which is easy to assemble and complete with but very little effort and expense.

Although thus particularly described, various changes in the construction, combination and arrangement of the parts may be made without departing from the spirit and scope of the invention.

I claim:

1. In a compact, a recessed base having a rear wall with a concave groove extending lengthwise along its inner face and top, a cover formed along its rear with a downwardly curved portion fitting into the concave groove of the base rear wall, an overhanging lip at the top of the groove, an outwardly extending rib at the bottom of the curved portion of the cover, and means fixed in the base recess engaging the under side of the cover curved portion to establish a hinged connection therewith whereby the cover is free to swing from a position flush with the base top through 90° or more, the cover rib and groove lip being substantially interengaged when the cover is in closed positioned.

2. In a compact, a flat base constituting the body portion of a container and recessed to form side and front and rear walls and provided along the rear wall at the inner face and top with a longitudinal concave groove provided with upper and lower edges projecting at an angle to the concave face of the groove, a cover formed along its rear edge with a downwardly curved portion fitting into the concave groove of the rear wall of the base and provided with a projecting lip movable between said projecting edges of the rear wall, and a hinge plug secured within 70 the base and having a rounded bead conforming

to the configuration of the curved portion of the cover and confining the same in said groove.

3. In a compact, a base recessed to form side and front and rear walls and provided in its rear wall with a concave groove extending lengthwise along the inner face and top of said rear wall, the side walls being provided at the ends of said groove with recesses, a cover formed along its rear edge with a downwardly curved portion fitting into the concave groove of the rear wall of the base, and a hinge plug provided with a rounded bead conforming to the configuration of the curved portion of the cover and confining said curved portion in said groove, said hinge plug being provided at its ends with lugs secured in the recesses of the side walls of the base.

4. In a compact, a base constituting the body portion of a container and recesses to form side, front and rear walls, the rear wall being provided with a concave groove extending lengthwise along its inner face and top and the side walls being provided at the ends of the groove with recesses, a cover formed along its rear edge with a downwardly curved portion fitting into the concave groove of the rear wall of the base, bosses projecting inwardly from the side walls of the

10
15
20
25

base at the recesses thereof and having curved edges fitting the curved portion of the cover, and a hinge plug provided at its ends with lugs secured in the recesses of the side walls between the bosses and shoulders formed by said recesses, said hinge plug being provided with a rounded bead conforming to the curvature of the curved portion of the cover and confining said curved portion in the groove of the rear wall.
